(57) **CLAIM**

The ornamental design for a liquor barn display as shown and described.

DESCRIPTION

FIG. 1 is a perspective view of a liquor barn display showing my new design;

FIG. 2 is a front side view thereof;

FIG. 3 is a rear view thereof;

FIG. 4 is a left end view thereof;

FIG. 5 is a right end view thereof;

FIG. 6 is a top plan view thereof; and

FIG. 7 is a bottom plan view thereof; and,

FIG. 8 is another perspective view of a liquor barn display thereof.

The long, dash, short dash broken lines shown in the figures show liquor bottles in FIGS. 1, 3, 4, 5, 6, and 8 and a roof dormer in FIG. 8 which depict environmental subject matter that forms no part of the claimed design. The remaining broken lines shown in the drawings represent portions of the liquor barn display that form no part of the claimed design.
